(57) **CLAIM**

The ornamental design for a front pack baby carrying system, as shown and described.

DESCRIPTION

FIG. 1 is a perspective view illustrating the front pack baby carrying system;

FIG. 2 is another perspective view illustrating the front pack baby carrying system of FIG. 1;

FIG. 3 is a front view illustrating the front pack baby carrying system of FIG. 1;

FIG. 4 is a rear view illustrating the front pack baby carrying system of FIG. 1;

FIG. 5 is a left side view illustrating the front pack baby carrying system of FIG. 1;

FIG. 6 is a right side view illustrating the front pack baby carrying system of FIG. 1;

FIG. 7 is a bottom view illustrating the front pack baby carrying system of FIG. 1;

FIG. 8 is a top view illustrating the front pack baby carrying system of FIG. 1;

FIG. 9 is a perspective view illustrating another front pack baby carrying system;

FIG. 10 is another perspective view illustrating the front pack baby carrying system of FIG. 9;

FIG. 11 is a front view illustrating the front pack baby carrying system of FIG. 9;

FIG. 12 is a rear view illustrating the front pack baby carrying system of FIG. 9;

FIG. 13 is a left side view illustrating the front pack baby carrying system of FIG. 9;

FIG. 14 is a right side view illustrating the front pack baby carrying system of FIG. 9;

FIG. 15 is a bottom view illustrating the front pack baby carrying system of FIG. 9;

FIG. 16 is a top view illustrating the front pack baby carrying system of FIG. 9;

FIG. 17 is a rear view illustrating the front pack baby carrying system of FIG. 1 with the carrying system laid flat; and,

FIG. 18 is a rear view illustrating the front pack baby carrying system of FIG. 9 with the carrying system laid flat.

The broken line showing of the mother and child are included for the purpose of illustrating the baby carrying system in use and forms no part of the claimed design.
